SUCTION SILENCER FOR INTERNAL COMBUSTION ENGINES

Frank Newton, Monterey, Calif.

Application March 27, 1939, Serial No. 264,501

5 Claims. (Cl. 181—51)

My invention relates to improvements in an apparatus for muffling and purifying exhaust gases.

An important object of my invention is to provide a muffler for rendering harmless the toxic gases of the exhaust of an internal combustion engine.

Another object of my invention is the provision of a muffler for purifying the exhaust gases and for subduing the exhaustive discharge thereof.

Yet another object of my invention is to provide a muffler that will substantially reduce the back pressure in the exhausting system of the vehicle.

Still another object of my invention is to provide a muffler that is durable in its construction and efficient in its operation.

Other objects and advantages of my invention will be apparent during the course of the following description.

In the drawing, forming a part of this specification, and in which like numerals are employed to designate like parts through the same,

Figure 1 is a longitudinal sectional view of a device embodying my invention.

Figure 2 is a vertical sectional view, taken on the line 2—2 of Figure 1.

Figure 3 is a vertical sectional view, similar to Figure 2, but showing a slight modification thereof.

Figure 4 is a longitudinal sectional view of another form of my invention.

Figure 5 is a perspective view, showing parts broken away of yet another form of my invention, and

Figure 6 is a fragmentary vertical sectional view, taken on the line 6—6 of Figure 4.

In the accompanying drawing, wherein for the purpose of illustration, are shown preferred examples of my invention, the numeral 10 designates a substantially tubular body portion having either end 11 and 12 thereof formed with transverse closure walls 13 and 14 which are formed with centrally located bosses 15 and 16. The inlet pipe 17, comprising a portion of the exhaust pipe leading from the manifold of the internal combustion engine (not shown), is received by the boss 16 and communicates with the interior of the tubular body portion 10 but terminates flush with the inner face of the wall 14. An outlet pipe 18, comprising a continuation of the exhaust pipe, is carried by the boss 15 and communicates with the interior of the body portion but terminates flush with the inner face of the wall 13. The body portion 10 is provided with

foraminated transverse closure walls 19, which are here illustrated as being two in number, however, it is to be understood that any number desired may be used. The walls 19 are spaced progressively closer together as they approach the outlet pipe 18 so that the compartments 20, 21 and 22 therebetween will become progressively smaller.

The heat conducting or ventilating tube 23 is positioned longitudinally of the body portion and in appressed relation with the inner periphery thereof. The tube 23 is received by aligning openings in the end walls 13 and 14 and intermediate walls 19, and the end 24 thereof terminates flush with the outer plane of the end wall 14 and communicative with the atmosphere exteriorly of the body portion 10. The end 25 of the tube 23 projects longitudinally beyond the end wall 13 and the open extremity 26 thereof is bent downwardly at substantial right angles 20 thereto as clearly illustrated in Figure 1. The inner diameter of the tube 23 is struck inwardly, as at 27, within the compartment 21 to form an opening 28 therein which will afford communication between the ventilating tube and the interior of the body portion 10.

The operation of my device is as follows:

The exhaust gases are introduced into the compartment 20 of the body portion 10 through the pipe 17, as indicated by the arrows in Figure 1. The compartment 20 is the largest of the three compartments 20, 21 and 22, and as the gases impinge against the first closure wall 19, the velocity of the same will be substantially decreased. As the gases and heat pass into the second compartment 21 a portion of the heat from the gases will flow through the opening 28 and into the ventilating tube 23. The removal of a quantity of heat from the gases in this compartment will result in a decrease in the pressure of the gases therein. The removal of the heat and the consequential reduction in pressure will result in a partial vacuum being formed within the body portion 10 and cool air will consequently rush in through the opening 29 of the ventilating tube 23. As soon as the air begins to enter through the opening 29 of the ventilating tube, a certain amount of heat will be absorbed from the compartment 21, resulting in a reduction in the pressure of the gases therein. The cool air entering the opening 29 will join the heated gases flowing through the opening 28 and will substantially cool the same sufficiently to absorb additional heat from the gases remaining within the intermediate compartment 21. This will re-

65

sult in a further reduction of the pressure of the gases within this compartment. The closure walls 19 substantially reduce the velocity of the gases to permit the cool air in the ventilating tube to effect a substantial decrease in the pressure of the gases within the body portions 10. By the time the gases have reached the last and smallest chamber 22 they will be greatly cooled and therefore reduced in pressure, and will be discharged through the pipe 18 under such reduced pressure as to be practically noiseless.

It may thus be seen that by directing a portion of the heat from the exhaust gases into the tube 23 in a manner whereby a suction is created to draw cool air through the opening 29, additional heat will be absorbed from the gases within the body portion 10 and the substantial cooling will effect a consequential reduction in pressure sufficient to prevent a back pressure from building up within the body portion 10 to prevent the complete scavenging of the cylinder at every stroke of the piston. This will greatly increase the efficiency of the vehicle, and effect a more complete scavenging in the combustion chamber 25 of the carbon dioxide gas, thereby permitting a more complete combustion of the fuel and removing one great cause of incomplete combustion as well as eliminating a large volume of carbon monoxide.

30 In the form of the invention, as illustrated in Figure 3, I have provided a plurality of the longitudinally extending ventilating tubes 23 spaced equally about the inner periphery of the body portion 10. The operation of this form of the invention is so similar to the form hereinabove described that no further explanation is thought to be necessary. It will be obvious, however, that the cooling effect will be greatly increased by the addition of the greater number of tubes. 40 This form of the invention is particularly adapted to be used in association with an airplane, or the like, where a comparatively great cooling effect is necessary.

In the form of the invention, as illustrated 45 in Figure 4, the tube 23 has a substantially smaller tube 30 disposed centrally therein and terminating a substantial distance from the end 29 thereof. The end 31 of the inner tube 30 is flared outwardly, as illustrated in Figure 4, and the end 32 thereof is provided with radially projecting ears 33 which engage the inner periphery of the tube 23. The segmental slots 34 are formed between the ears 33, and permit a passage of the heated gases within the three compartments 28, 21 and 22 to pass through the ports 35 in the ventilating tube 23 and to flow through the segmental slots 34 between the end 32 of the inner pipe and the inner periphery of the ventilating tube 23. The reduction of pressure interiorly of the body portion 10 will cause cool air to be drawn in the end 31 of the tube 30, and a substantial cooling of the gases and a consequential reduction in the presence of the gases within the body portion will be effected, in the 65 same manner hereinbefore described.

In the form of the invention, as illustrated in Figure 5, the tube 23 is formed with a longitudinally extending, horizontally disposed, wall 36 that divides the end 24 of the tube into an upper 70 compartment 33 and a lower compartment 39. The end 24 of the upper compartment 33 is provided with an end closure wall 37 which prevents atmospheric communication with the upper compartment 33. The lower compartment 39 75 is free to communicate with the atmosphere.

The upper surface of the tube 23 is provided with a plurality of apertures 40, through which the heated gases from within the body portion 10 may pass. As the gases flow toward the rearward end 25 of the ventilating tube, the cooling air will be drawn in through the lower end of the compartment 39 to perform the same function as hereinbefore described.

It is to be understood that the forms of my invention, herewith shown and described, are to be taken as preferred examples of the same, and that various changes in the size, shape and arrangement of parts may be resorted to without departing from the spirit of my invention, or the scope of the appended claims.

Having thus described my invention, I claim:

1. A muffler comprising a tubular body having transverse closure walls at either end thereof adapted to centrally receive portions of an exhaust pipe in a manner whereby exhaust gases 20 will longitudinally traverse the body; a plurality of foraminated transverse partitions intermediate the end walls dividing the said body into chambers; and a tubular member extending through the body and said partitions laterally of the longitudinal axis of the body, the ends of the said tubular member opening through the end closure walls and communicating with the atmosphere and an intermediate portion thereof opening into at least one of the said compartments.

2. A muffler comprising a tubular body portion having transverse closure walls at its opposite ends adapted to centrally receive portions of an exhaust pipe in a manner whereby heated exhaust gases will longitudinally traverse the body for its entire length; a plurality of foraminated partitions dividing the said body into chambers; a tubular member received by the body laterally of the longitudinal axis thereof, the ends of the said member opening through the end closure walls of the body and having communication with the atmosphere, an intermediate portion of the member communicating with the chambers of the body intermediate its ends in a manner whereby a rapidly flowing stream of substantially cool atmospheric air may longitudinally traverse the tubular member to cool the heated exhaust gases in the body by heat absorption and to create a suction to draw a portion of the gases from the said body.

3. A muffler comprising a tubular body having transverse closure walls at either end thereof adapted to receive portions of an exhaust pipe in a manner whereby exhaust gases will longitudinally traverse the body; a plurality of foraminated transverse partitions intermediate the end walls and dividing the said body into chambers; and a plurality of spaced tubular members positioned circumferentially around the said body and concentrically of the longitudinal axis thereof, the opposite ends of the tubular members operating through the end walls of the body and communicating with the atmosphere, each of the tubular members communicating with at least one of the said compartments at a point intermediate the ends thereof whereby a rapidly flowing stream of atmospheric air may longitudinally traverse each of the tubular members to create a suction to draw a portion of the exhaust gases from the body.

4. A muffler comprising a tubular body having closed ends adapted to receive portions of an exhaust pipe in a manner whereby heated exhaust gases will longitudinally traverse the body for

its entire length; foraminated transverse partitions dividing the body into a plurality of chambers of progressively decreasing size toward the exhaust discharge end of the body; a perforated 5 tubular member extending longitudinally through the body and partitions laterally of the longitudinal axis of the body and with the opposite ends thereof opening through the closed ends of the body; and a second imperforate tubular 10 member disposed coaxially within the first tubular member and adapted to be longitudinally traversed by a stream of atmospheric air, the entrance end of the second tubular member being formed to seal the corresponding end of the 15 first tubular member and the discharge end thereof being formed to permit passage of exhaust gases from the body through the discharge end of the first tubular member, whereby the rapid flow of atmospheric air through the second 20 tubular member will create a suction to draw gases from the body.

5. A muffler comprising a tubular body having closed ends adapted to receive portions of an exhaust pipe in a manner whereby the heated

exhaust gases will longitudinally traverse the body for its entire length, foraminated transverse partitions dividing the body into a plurality of chambers of progressively decreasing size toward the exhaust discharge end of the body, a 5 tubular member extending longitudinally through the body and partitions laterally of the longitudinal axis of the body and with its opposite ends opening through the closed ends of the body, a partition received by the tubular member for di- 10 viding the same into an upper and a lower passage, the end of the upper passage at the inlet end of the body being closed and the portion of the tubular member enclosing the upper passage being perforate to permit the heated gases in 15 the body to have access thereto, the lower passage being open at its ends to permit a stream of comparatively cool atmospheric air to longitudinally traverse the same to cool the heated gases in the upper chamber and body by heat 20 absorption and to create a suction to draw a portion of the exhaust gases from the said body.

FRANK NEWTON.
